UNITED STATES PATENT OFFICE.

CLAUD D. CURRY, OF MEMPHIS, TENNESSEE.

PAPER-ASSOCIATING MACHINE.

1,117,000.

Specification of Letters Patent. Patented Nov. 10, 1914.

Application filed August 24, 1910. Serial No. 578,713.

To all whom it may concern:

Be it known that I, CLAUD D. CURRY, of Memphis, in the county of Shelby and State of Tennessee, have invented certain new and useful Improvements in Paper-Associating Machines; and I do hereby declare the following to be a full, clear, and exact description of the invention, such as will enable others skilled in the art to which it appertains to make and use the same.

This invention relates to improvements in paper associating machines, and particularly to such as are operable to assemble or "stuff" newspapers and signatures of magazines or other books.

One object of my present invention is to so construct a machine for the purpose stated that the paper sections will be accurately and rapidly assembled, with inner sections or collections of sheets neatly within an outer section or collection of sheets.

A further object is to provide improved opening means for a paper section and means for properly holding the same open until an inner section (or sections) shall have been inserted.

A further object is to so construct the machine that it will operate to feed an outer paper section from a receptacle to a plurality of opening mechanisms, and then feed inner sections from a plurality of receptacles and insert them into the outer sections in the opening mechanisms.

A further object is to provide, in a paper assembling or stuffing machine, improved needle mechanism for opening a folded paper section or collection of sheets at the folded edges thereof and improved devices for spreading out the loose edges of the folded paper section.

A further object is to so construct the machine that it will operate to open a folded paper section and hold the same taut while the nose of a spreader or opener is entering between folds of a paper.

With these objects in view, the invention consists in certain novel features of construction and combinations of parts as hereinafter set forth and pointed out in the claims.

In the accompanying drawings; Figure 1 is a longitudinal sectional view of a machine embodying my improvements; Fig. 2 is a side elevation; Fig. 3 is a horizontal sectional view showing the stuffing or assembling mechanism; Fig. 4 is an enlarged

view partly in plan and partly in section showing the needle box construction of the stuffing or assembling mechanism and means for operating the same; Fig. 5 is a vertical transverse section through the stuffing or assembling mechanism, and showing also portions of the feeding devices; Fig. 6 is a plan view showing the opening devices of the stuffing mechanism and operating means therefor; Fig. 7 is a side elevation of the structure shown in Fig. 6; Fig. 8 is an enlarged detail view illustrating the traveling opener or spreader, Figs. 9, 10, 11 and 12 are detail views of the needle box structure for the stuffing mechanism. Fig. 13 is a diagrammatical view illustrating the travel of the paper sections.

1 represents a framework, in the upper portion of which a plurality of hoppers or magazines 2, 3, 4, are located, each in an inclined position as clearly shown in Figs. 1 and 2. Below the several magazines, mechanisms for withdrawing the paper sections from the magazines and feeding them to the opening and stuffing mechanism, are located. These feeding mechanisms constitute the subject matter of a separate application for patent filed on even date herewith and designated by Serial No. 578,714 and need not be specifically described herein; the claims of this case being directed to the opening and stuffing mechanism.

Located some distance below the throat (which constitutes the outlet of the first feeding mechanism) are two shafts 72 and 73, the latter being mounted in a manner to permit it to rock. These shafts are spaced apart and between them, the upper end of a curved discharge chute 74 is disposed. The rock-shaft 73 is provided with fixed depending arms 75 and each of these arms carries shelf or support 76 for a paper section, said shelves or supports normally projecting over the top of the discharge chute 74. The rock-shaft 73 is also provided with a fixed arm 77, with which, one arm of a bell-crank-lever 78 is connected, the other arm of said bell-crank being provided with a pin or roller to coöperate with a cam 79 on one of a pair of shafts 80. It is apparent that during a portion of the rotation of the cam 79, motion will be transmitted to the rock-shaft 73 to turn the same in a direction to move the shelves or supports 76 downwardly to release the stuffed paper sections to the discharge chute 74, and that during another

portion of the rotation of the cam 79, the shaft 73 will be rocked in a direction to raise the shelves or supports 76 to normal position.

5 In dropping from the throat of the feed mechanism to the shelves or supports 76, a paper section will enter between two needle boxes 81, and two clamps 82, the needle boxes being so located as to engage the paper section near one end of the latter and the clamps being so located as to engage the paper section near the other end thereof, and these needle boxes and clamps are so constructed and operated that they will engage 10 a paper section when it drops on the shelves 76, and sustain the paper section in an upright position and prevent the same from collapsing or doubling. The clamps 82 are carried by heads 83 on brackets 84 loosely 15 mounted on the shafts 72 and 73 as shown in Fig. 5. One of the clamps is movably supported and is rendered yielding by the action of a spring 85.

The brackets 84 are made with laterally 20 projecting arms 86 provided with rollers at their outer ends to coöperate with cams 87 on shafts 88. These cams are so formed and located on the shafts 88 and the latter are driven at proper speed to cause the operation 25 of the clamps to engage the paper section as soon as it shall have dropped upon the shelves or supports 76, and when the cams 87 shall have passed the bracket arms 86, the brackets 84 will be pulled back by 30 the operation of springs 89 and the clamps caused to release the paper section.

The needle boxes 81 above referred to are carried by frames 90 which are mounted loosely at their lower ends on the shafts 40 72—73. The frames 90 are provided with arms 91 which carry rollers 92 at their free ends to coöperate with cams 93 on shafts 88 to which latter motion is imparted by means of suitable gearing. By means of the cams 45 93 the needle boxes are moved toward each other to engage a paper section between them and away from each other to permit the insertion of a paper section between them.

50 In constructing each needle box 81, I provide a head 95 comprising a member 96 secured rigidly to one of the frames 90 and two parallel members 97 at respective ends of the member 96. The parallel members 55 97 are made with beveled forward edges 98 and are provided on their outer faces with parallel ribs 99. A face plate 100 rests against the beveled edges of the members 97 of the head and is provided with holes 60 101 for the passage of needles as hereinafter explained. The face plate 100 is provided at each of its ends with parallel members 102 having grooves 103 for the reception of the ribs 99 on the outer faces of the members 65 97 of the fixed head 95, and the members 102

are also provided with slots 104 for the passage of screws 105 which enter the members 97 of the fixed head. The face plate is provided at one edge with a flange or projection 106, in which an adjusting screw 107 (Fig. 4) is swiveled, said screw entering a threaded socket 108 in one edge of the member 96 of the fixed head 95. By these means, the perforated face plate through which the needles pass can be readily adjusted. The members 97 of the fixed head are provided 70 on their inner faces with ribs 109 (Fig. 9) to enter grooves in a needle carrier 110 disposed between the members 97 of said fixed head and having its portion adjacent to the face plate 100 beveled so as to be disposed parallel with the latter. The carrier 110 is made with a plurality of parallel holes 111 (preferably arranged in rows) for the accommodation of needles 112, the latter being 75 held adjustably in place by means of screws 113—114, as shown in Fig. 12. A shaft 115 is mounted in lugs 116 at respective ends of the fixed head (Fig. 9) and provided with arms 117 having pins 118 to engage the 80 needle carrier. The shaft 115 is also provided with an arm 119 (Figs. 4 and 9) which carries a roller 120 (Fig. 9) at its free end to coöperate with a cam 121 for reciprocating the needles. The cam 121 is 85 carried by a shaft 122 mounted in frame 90. The shaft 122 in each needle box frame 90 is provided at one end with a pinion 123 (Figs. 1, 3 and 4) which receives motion from a pinion 124 on a shaft 125. Each 90 shaft 125 is mounted in a bracket 126 hung on shaft 122 and the other end of said shaft 125 has connection with a beveled gear 127 mounted in a bracket 128 sustained by shaft 88 and the shafts 88 have beveled gears 129 secured thereto to transmit motion to the 95 gears 127 on the shafts 125. Motion is transmitted from the shafts 125 to the shafts 122 (by means of the pinions 123—124) to operate the cams 121 for imparting motion 100 to the needle carriers.

After a paper section shall have been deposited between the pair of clamps 82 and the pair of needle boxes 81, the end of said paper section farthest removed from the 105 needle boxes will be engaged by horizontally disposed rotary grippers 130—131 shown in Fig. 3, for the purpose of drawing the paper section taut lengthwise. The gripper 130 is carried by a fixed arm 132 projecting from 110 a bracket 133 secured to the framework, and said bracket has mounted therein, a short shaft 134 provided at one end with a bevel gear 135 which receives motion from a bevel gear 136 on one of the shafts 88. The other 115 end of the short shaft 134 is provided with a bevel gear 137 which transmits motion to a bevel gear 138 on a stub shaft 139 (Fig. 7) and the other end of this stub shaft is provided with a spur gear 140 which meshes 120 125 130

with and transmits motion to a gear 141 carried by the gripper 130. The gearing for operating the gripper 131 is the same in construction as above described in connection with the gripper 130, and has the same reference characters applied thereto. The gripper 131 however, is carried by one member of a pivotally-supported L-shaped arm 142 so that the gripper 131 can have a movement relatively to the gripper 130. To one member of the L-shaped 142, one end of a spring 143 is connected, the other end of said spring being adjustably attached to the framework. With this construction the paper section can be caused to be engaged by the grippers with any desired pressure and the frictional contact of the grippers with the paper section will be sufficient to cause the paper section to be drawn taut during the rotation of said grippers.

After a paper section shall have become disposed and held between the needle boxes 81, clamps 82 and grippers 130—131, and the needles shall have been projected into the members of the folded paper section near one corner of the latter, the cams 93 on the shafts 88 will operate to swing the frames 90 and thus move the needle boxes 81 away from each other, carrying the corners of the folded paper section with them and opening said paper section at one end. In order that the paper section shall be fully opened to receive an insert paper section, I employ spreading devices presently described, and as these spreading devices operate to open out the paper section, the grippers move away from said paper section by the operation of the cams 87 on the shafts 88.

In constructing the spreading devices, I employ two horizontal parallel endless chains 144 movable in guides 145, the latter being disposed below and at respective sides of the discharge throat 71 of the feeding mechanism so that a paper section can pass from said throat to the opening devices below. The chains 144 pass about sprockets 146 on short vertical shafts 147, and past suitably disposed idlers 148. Pulleys or plain wheels 149 are secured to the shafts 147 at or near the lower ends of the latter, for the accommodation of straps 150 carried by arms 151 secured to and depending from the endless chains 144, as shown in Figs. 5 and 7. Each strap 150 is of a length approximately equal to the length of a paper section, and at one end of each strap, one member of a spreader 152 is located. The chains move continuously and their operation is so timed that the two members of the spreader will arrive near the end of a paper section at the same time and coöperate in passing between the members of the paper section, to spread said members apart; thus fully opening said

paper section to permit the reception of an "insert".

After an "insert" has been deposited between the members of an opened paper section, the shaft 73 will be rocked to withdraw the shelves or supports 76 for the purpose of releasing the "stuffed papers". The said stuffed papers will be guided to the chute 74 by guides 153 (Fig. 5) and they will be forced into and through said chute by means of rotary discharging rolls 154. These rolls are located on the shafts 80 and their operation is so timed by means of intermitting gearing that they will close against the stuffed paper sections after the shelves or supports 76 shall have been withdrawn.

I have thus far described one unit of the machine. Three feeding mechanisms are shown in Fig. 1 of the drawings, and they are all the same in construction and operation. Fig. 1 of the drawing also shows two opening and stuffing mechanisms, which are the same in construction and operation, and they may, for convenience, be designated by the reference characters, A and B. The magazine 2 is intended to contain outer paper sections and the magazines 3 and 4 are to contain "inserts". The feeding devices indicated at *a* Fig. 13 between the magazine 2 and the opening device A constitute a sheet path from said magazine 2, and the feeding devices *b* between the magazines 3 and 4 and the opening device B constitute second sheet paths from these magazines. A cross sheet path is provided by the feeding devices indicated at *c*, and a second cross sheet path is provided by the feed devices indicated at *d*. The first or bottom outer paper section from the magazine 2 will be fed downwardly and will be guided by suitably arranged feed belts as shown in Fig. 1, to the first throat 71 and from the latter to the opening and stuffing mechanism A, where it will be opened as before explained for the reception of "inserts". These "inserts" will be guided by suitably arranged belts as shown in Fig. 1, from the feeding mechanism under the magazines 3 and 4 to the throat 71 over the stuffing mechanism A, and dropped (side by side) between the members of the opened or spread paper section therein, after which the whole will be discharged through the chute 74.

The next outer paper section fed from the first magazine will follow the route of the preceding one, until it reaches the throat 71. At this point, the said second outer paper section from the magazine 2 will be diverted by means of a switch 155, and will be conveyed by suitably arranged feeding tapes as shown in Fig. 1 and deposited into the opening and stuffing mechanism B. The next two inserts from the magazines 3 and 4

will also be diverted by a switch 156 and caused to drop (side by side) between the opened or spread members of the outer paper section in the opening and stuffing mechanism. It is apparent that the third outer paper section from magazine 2 and the inserts from the other magazines will, (by the action of the switches 155 and 156) be directed to the stuffing mechanism A.

10 The papers will, therefore, be stuffed alternately in the stuffing mechanisms A and B.

In Fig. 13, cover sheets 1A and 1B are shown in the stuffing mechanisms A and B respectively, and inserts for these covers are also shown in place. Fig. 13 also shows the relative positions of covers 2A and 3A and their inserts to be assembled in the mechanism A, and the relative positions of covers 2B and 3B and their inserts to be assembled in the mechanism.

20 If a single opening or stuffing mechanism were employed, the paper sections would be run in so close together that said mechanism could not properly operate, and would assemble one paper before another paper would arrive. By providing two opening or stuffing mechanisms, and feeding the paper sections alternately to these mechanisms, as previously explained; double the space is afforded to open one section and insert another, than could be had if but a single mechanism were employed. Furthermore, the construction and operation of the machine as previously explained, permits 30 the paper sections to run at one-half the velocity than that which would be attained if but a single opening or stuffing mechanism were employed.

The discharge chutes 74 from the two 40 opening and stuffing mechanisms deliver the stuffed papers to conveyer belts 162 which carry the stuffed papers rearwardly and them upwardly and discharge them at 163, onto a conveyer 164, onto which they are 45 properly directed by a feed reel 165.

Having fully described my invention what I claim as new and desire to secure by Letters-Patent, is:—

1. A paper associating machine comprising a magazine for paper sections, a second magazine for paper sections, a spreading device for the paper sections, a second spreading device for the paper sections, a sheet path leading from the first magazine to the 50 first spreading device, a second sheet path leading from the second magazine to the second spreading device, a cross sheet path leading from the first sheet path to the second path, a second cross sheet path leading 55 from the second sheet path to the first sheet path, switching mechanism controlling passage from the first sheet path to the first cross sheet path, and from the second cross sheet path to the first sheet path, and a second switching mechanism controlling pas-

sage from the second sheet path to the second cross sheet path.

2. A paper associating machine comprising two magazines for paper sections, two spreading mechanisms for paper sections, 70 and means for feeding paper sections from both of the magazines to the two spreading mechanisms in alternation.

3. A paper associating machine comprising a magazine for paper sections, two other 75 magazines for paper sections to be inserted in the paper section of the first magazine, two spreading mechanisms, means for feeding paper sections from the first magazine alternately to the two spreading mechanisms, 80 and means for concurrently feeding alternate paper sections from the two other magazines of the two spreading mechanisms in alternation with the paper section from the first magazine.

25 4. A paper associating machine comprising a magazine for paper sections, a second magazine for paper sections, a spreading device, a sheet path leading from the first magazine to the first spreading device, a 90 sheet path leading from the second magazine to the second spreading device, cross sheet paths connecting said sheet paths, and switch devices at the junctions of the cross sheet paths with the other sheet paths.

5. A paper associating machine comprising a magazine for paper sections, a second magazine for paper sections, a spreading device, a second spreading device, sheet paths leading from the first and second magazines 100 to the first and second spreading devices respectively, two cross sheet paths connecting the first mentioned sheet paths, and switches at the junctions of said sheet paths, one of said switches being operable to control the 105 passage of sheets from the first magazine alternately to the first and second spreading device, and the other switch being operable to control the passage of sheets from the second magazine alternately to the first and 110 second spreading devices.

6. A paper associating machine comprising a magazine for folded sheets, a plurality of magazines for insert sheets, two spreading devices, sheet paths between said magazines and spreading devices, the sheet paths from the insert magazines communicating with each other, switch mechanism for directing folded sheets from the folded sheet magazine to said spreading devices alternately, and switch mechanism for directing insert sheets from all of the other magazines to the two spreading devices alternately, whereby said insert sheets will enter the folded sheets deposited alternately in 125 said spreading devices.

7. A paper associating machine comprising a magazine containing folded cover sheets, a plurality of magazines containing insert sheets, means for associating said in- 130

sert sheets side by side, and means for inserting said associated insert sheets within a cover sheet.

8. A paper associating machine comprising a magazine containing folded cover sheets, a plurality of magazines containing insert sheets, means for separating the folds of the cover sheet, means for leading a cover sheet from the magazine to the separating means, means for associating insert sheets side by side from the plurality of magazines, and means for feeding the associated insert product to the open cover in the separating means.

15. 9. In a machine of the character described, the combination with means for separating portions of a folded paper section, of a traveling spreader movable between the members of the paper section and operating 20 to open the same out and means for depositing an "insert" within the opened paper section.

10. In a machine of the character described, the combination with supporting 25 means for a folded paper section, and means for separating corners of said paper section, of a traveling spreader movable between the members of the paper section for opening or spreading the same, and means 30 for depositing an insert into the opened or spread paper section.

11. In a machine of the character described, the combination with means for supporting a folded paper section at the folded 35 edge of said section, of means for sustaining the paper section taut in an upright position, means for separating the corners of the paper section at one end thereof, and a traveling spreader movable between the 40 members of the paper section for opening the same.

12. In a machine of the character described, the combination with supporting means for a folded paper section, and means 45 for separating corners of the folded paper section at one end of the latter of parallel conveyers, and coöperating spreader members carried by said conveyers for opening said paper section.

50 13. In a machine of the character described, the combination with supporting means for a folded paper section and means for separating the corners of said paper section at one end thereof, of parallel endless 55 chains, and a spreader member connected with each chain, said spreader members disposed to coöperate with each other to spread or open the folded paper section.

60 14. In a machine of the character described, the combination with supporting means for a folded paper section, and means for separating the corners of said paper section at one end thereof, of two endless chains disposed parallel with each other and 65 spaced apart, arms depending from each

chain, straps secured to the arms of each chain and extending from one of said arms to another, and a spreader member at one end of each strap, the spreader members arranged to coöperate with each other to travel 70 between the members of the paper section and spread or open the same.

15. In a machine of the character described, the combination with means for supporting a folded paper section, and means 75 for separating the corners of the paper section at one end thereof, of two pairs of vertical shafts above the plane of said separating means, a sprocket wheel and a plain wheel carried at respective ends of each of 80 said shafts, sprocket chains engaging the sprocket wheels of each pair, whereby said sprocket chains are disposed parallel with each other and spaced apart, plain wheels at the lower ends of said shafts, two arms depending from each sprocket wheel, a strap connecting the arms of each sprocket chain and adapted to run on said plain wheels, and a spreader member located at one end of each of said straps, said spreader members disposed to coöperate with each other and pass between the members of the folded 85 paper section to spread or open the latter.

16. In a machine of the character described, the combination with supporting 95 means for a folded paper section, of separating means disposed to engage the paper section at one end thereof, clamps disposed to engage the paper section near the other end, opening or spreading means to pass between the members of the paper section, means for operating the clamps, and operating devices for the separating and opening or spreading means.

17. In a machine of the character described, the combination with means for supporting a folded paper section, and separating means to engage the members of the folded paper section at one end of the latter, of two swinging brackets, clamps carried by said brackets to clamp the other end of the paper section, spreading means movable between the members of the paper section, and cam devices for operating said 110 swinging arms to operate the clamps. 115

18. In a machine of the character described, the combination with means for supporting a folded paper section, of separating devices movable toward and away from one end of said paper section near one end of the latter, means for operating said separating devices, swinging brackets, clamps carried by the swinging brackets for engaging the other end of the paper section, cam devices for operating said clamps, opening or spreading devices movable between the members of the folded paper section, and means for operating said opening or spreading devices. 120

19. In a machine of the character de- 130

scribed, the combination with supporting means for a folded paper section, of separating devices for the paper section, comprising two swinging frames, needle boxes carried by said frames, needles carried by said needle boxes, means for swinging said frames and moving the needle boxes relatively to each other and to the respective members of the folded paper section, and means for reciprocating the needles of the needle boxes.

20. In a machine of the character described, the combination with means for supporting a folded paper section, of separating means for the members of the paper section, comprising two heads, means for moving said heads toward and away from each other and the respective members of the paper section, carriers supported by each head, needles supported by each carriers, means for reciprocating said carriers, and traveling spreading means movable between said heads and between the members of the paper section.

25. 21. In a machine of the character described, the combination with supporting means for a folded paper section, of separating means comprising two swinging frames, heads on said frames and movable with the latter toward and away from each other, carriers movable on said heads, needles secured to said carriers, means carried by the swinging arms and connected with the carriers for operating them, and spreading means movable between said heads and between the members of the paper section.

22. In a machine of the character described, separating means for the members of a folded paper section, comprising two relatively movable heads, means for moving said heads relatively to each other and the paper section, carriers movably mounted on said heads, needles adjustably secured to said carriers and projecting therefrom, and means for reciprocating said carriers.

23. In a machine of the character described, separating means for a paper section comprising two relatively movable heads, a face plate adjustably secured to each head and having a plurality of perforations, a carrier movably mounted on each head, a plurality of needles secured to each carrier and movable through the perforations of the adjacent face plate, and means for reciprocating said carrier.

24. In a machine of the character described, separating means for a folded paper section, comprising two relatively movable heads, each provided with guide members, a perforated face plate for each head and provided with guide members to

engage the guide members of the head, means adjustably securing the guide members of the face plates to the guide members of the head, a reciprocating carrier disposed between the guide members of each head, needles secured to each carrier and passing through the perforations of the adjacent face plate, means for moving said heads relatively to each other and relatively to a paper section between them, and means for independently reciprocating the needle carriers.

25. In a machine of the character described, the combination of a plurality of opening mechanisms, a plurality of magazines, a plurality of feeding mechanisms for directing paper sections to the opening mechanisms, means for directing paper sections fed from one of said magazines alternately to the respective opening mechanisms, and means for directing paper sections fed from the other magazines to the opened paper sections in the respective opening mechanisms.

26. In a machine of the character described, the combination of two opening mechanisms, two magazines for outer paper sections and "inserts" respectively, feeding mechanisms between the magazines and opening mechanisms, means for directing outer paper sections to the feeding mechanisms alternately, and means for directing "inserts" alternately into opened paper sections in the respective opening mechanisms.

27. In a machine of the character described, the combination of two opening mechanisms for paper sections, a magazine for outer paper sections, mechanism for feeding paper sections from said magazine, alternately to said opening mechanisms, a plurality of magazines for "inserts", and mechanism for feeding "inserts" from all of said last-mentioned magazines to said opening mechanisms alternately.

28. In a machine of the character described, the combination of a plurality of paper-section opening devices, a plurality of magazines, means for removing paper sections from the magazines and feeding them to the opening devices alternately, discharge passages communicating with the opening devices and conveying means in position to receive stuffed papers from said discharge passages.

In testimony whereof, I have signed this specification in the presence of two subscribing witnesses.

CLAUD D. CURRY.
